UNITED STATES PATENT OFFICE

JAMES C. REA, OF SAN FRANCISCO, CALIFORNIA, ASSIGNOR TO PACIFIC ELECTRIC MANUFACTURING CORPORATION, OF SAN FRANCISCO, CALIFORNIA, A CORPORATION OF CALIFORNIA

ELECTRICAL SWITCH

Application filed July 12, 1929. Serial No. 377,735.

This invention relates generally to the construction of electrical switches, particularly switches utilized in connection with high tension electrical power distribution.

5 It is a general object of this invention to devise novel and improved apparatus for carrying a plurality of switch elements of a multi-pole switch, whereby these elements can be rocked or oscillated in unison to 10 operate with relatively stationary switch elements.

It is a further object of this invention to 15 devise a rocking or oscillating mechanism of the character outlined above, which will be reliable in operation and which will not be detrimentally effected by adverse weather conditions.

It is a further object of this invention to 20 provide novel means which will facilitate the adjustment of a plurality of pins or arms, for carrying movable elements of a multi-pole electrical switch.

It is a further object of this invention to 25 devise an effective structure of the above character which can be readily assembled on elevated towers or platforms.

It is a further object of this invention to 30 devise a multi-pole electrical switch having relatively small pivot pins upon which the switch element supporting pins can be rocked, and which also incorporates additional means whereby the switch pins are normally connected together to move in unison.

35 Further objects of the invention will appear from the following description in which I have set forth the preferred embodiment of my invention. It is to be understood that the appended claims are to be accorded a range of equivalents consistent with the state of the 40 prior art.

Figure 1 is a side elevational view of a multi-pole switch incorporating my invention.

45 Fig. 2 is a side elevational detail, illustrating my rocker bearing and its associated parts on an enlarged scale.

50 Fig. 3 is a detail view similar to Fig. 2, but showing the parts in transverse cross section with the pins or arms in a different operating position.

Fig. 4 is a cross sectional detail taken along the line 4—4 of Fig. 2.

Fig. 5 is a cross sectional detail taken along the line 5—5 of Fig. 2.

Fig. 6 is a detail perspective view illustrating a preferred construction for one of the journal brackets which I employ. 55

Fig. 7 is a detail perspective view of a spacer member utilized in my construction.

Fig. 8 is a detail perspective view of another part of my apparatus. 60

Fig. 9 is a side elevational detail taken along the line 9—9 of Fig. 1.

That form of my invention illustrated in the drawings includes a plurality of switch arms 11, serving to carry a plurality of movable switch elements or blades 12. Blades 12 are arranged to cooperate with a plurality of relatively stationary switch elements or contacts 13. Switch elements 12 are mounted upon suitable insulators 14, which in turn are mounted upon the ends of arms 11. Stationary switch elements 13 are shown carried by insulators 16, which in turn are mounted upon the platform or switch support 17. 70 Connections to the movable switch elements 12 can be made thru flexible conductors 18, which connect these elements to the stationary terminals 19. 75

With a switch of the above character, it is 80 common to mount the arms 11 in such a manner that they can be swung from closed position shown in full lines in Fig. 1, to a position such as illustrated in dotted lines in this figure, to disconnect elements 12 from the stationary elements 13. In the past this movement has been accomplished by mounting arms 11 upon a common rocker shaft. This construction is subject to many disadvantages. For example the rocker shaft must be 85 relatively large in diameter to provide adequate strength, and such a shaft requires a relatively large journal or bearing for each of the arms 11. The use of large bearings is not only expensive but they offer considerable friction and are apt to be detrimentally affected by adverse climatic conditions. 90

In my invention in place of utilizing a single rocker shaft for connecting together the arms 11, I employ a plurality of separate 100

small pivot pins, and a separate bar is employed for connecting together arms 11 so that these arms will move in unison. Thus referring to the drawings, I utilize a suitable journal bracket 21 in conjunction with each arm 11, this bracket having a base portion 22 to facilitate mounting upon the platform 17 or other support. A pivot pin 23 of relatively small diameter is journaled in the upper portion of each bracket.

In order to secure the arms 11 to their corresponding pivot pins 23, each arm is shown provided with a lower flanged portion 24, and interposed between this portion and the corresponding pivot pin 23, there is a spacer or upper clamping plate 26. Positioned upon the under side of each pin 23 and adapted to be secured to the corresponding arm 11, there is a member 27, which can be a metal casting similar to that shown in Fig. 8. In this instance member 27 is provided with a flange portion 28 to facilitate connection to arm 11, and is also provided with another flange portion 29 at its opposite end.

For properly engaging and retaining pin 23, the lower face of member 26 is provided with a depending portion formed to provide a notch 31 while the upper face of member 27 is provided with a corresponding notch 32. Notches 31 and 32 are adapted to fit upon the upper and lower sides of pivot pin 23 as shown in Fig. 2. In order to accommodate the upper portion of journal bracket 21, member 26 is provided with a slot 33, while member 27 is correspondingly bifurcated to provide a slot 34. For properly clamping member 27 to the corresponding member 26, registering apertures are provided to accommodate a plurality of clamping bolts 36, generally two or more clamping bolts being provided upon each side of the pivot pin 23. When bolts 36 are tightened, they serve to securely clamp members 26 and 27, upon the end portions of pivot pin 23, thus causing this pin to rotate together with arm 11 and to journal within bracket 21.

In order to cause all of the arms 11 to rock in unison, I have shown a relatively rigid metal rod or bar 37 extending transversely of the arms 11, and spaced from but substantially parallel to the line of centers of pivot pins 23. This rod is rigidly secured to each of the members 27, this being conveniently accomplished in each instance by the use of U-bolts 38 each of which surround bar 37 and extend thru apertures provided in flange portion 29.

In assembling the parts of my switch, the journal brackets 21 are first secured to the platform 17 or other support, in spaced relationship and with the axes of pivot pin 23 in alinement. The individual arms 11 are then clamped to the separate pivot pins 23, by properly assembling members 26 and 27. With arms 11 swung back in open switch po-

sition shown in dotted lines in Fig. 1, bar 37 can be lifted over the stationary switch elements 13 and positioned beneath the members 27, after which this bar is clamped in position by means of U-bolts 38. After bar 37 has been connected, the angular position of each individual arm 11 can be adjusted so that each of the switch elements 12 properly engages its corresponding stationary element 13, when the switch is in closed position. This can be accomplished by tightening or loosening the bolts 36 upon either side of the pivot pin 23, thus changing the angularity between a switch arm 11 and the corresponding member 27. When the proper angular position has been secured, bolts 36 are tightened to keep the desired final adjustment.

The switch arms 11 can be rocked from open to closed positions by any desired means. For example I have shown a lever 41 secured to shaft 37, and connected to reciprocable actuating rod 42.

My device can be operated with a minimum amount of friction, due to the small pivot pins 23, although the connection between the arms is sufficiently rigid to prevent sagging. Furthermore the manner of journaling the arms makes operation reliable at all times irrespective of climatic conditions.

I claim:

1. In a multipole electric switch, a plurality of switch arms, switch elements carried by said arms, a lever member associated with each of said arms, adjustable coupling means connecting each of said switch arms with its associated lever member, a pivot pin for each switch arm embraced by said coupling means, said pivot pins being in substantial alinement and a rigid bar interconnecting all of said lever members and extending substantially parallel to the axis of alinement of said pivot pins.

2. In a multipole electrical switch, a plurality of spaced switch arms adapted to extend in the same general direction, switch elements carried by said arms, a bar extending laterally of said arms, members adjustably secured to corresponding ends of said arms, means for rigidly connecting said members to said bar, pivot pins retained between the arms and said members, and relatively stationary journal means engaging said pins whereby the arms can rock in unison.

3. In a multipole electrical switch, a plurality of spaced switch arms adapted to extend in the same general direction, switch elements carried by said arms, a bar extending laterally of said arms, members adjustably clamped to corresponding ends of said arms, means for rigidly connecting said members to said bar, pivot pins interposed between the arms and said members whereby they extend in alinement along an axis spaced but parallel with respect to the bar, and stationary journal brackets engaging said pins.

4. In an electrical switch, a switch arm, a switch element carried by one end of said arm, a pivot pin disposed at the other end of the arm and extending laterally thereto, a member secured to the arm for securing the pin to the arm end, said member being bifurcated, means for securing said member to the arm, and a relatively stationary journal bracket extending within the bifurcated portion of said member and engaging the pivot pin.

5. In a device of the character described, a switch arm, a switch element carried by one end of said arm, a pivot pin disposed at the other end of the arm and extending laterally thereto, a member secured to the arm for securing the pin to the arm end, said member being bifurcated, means for securing said member to the arm for angular adjustment of the arm relative to said member, and a relatively stationary journal bracket extending within the bifurcated portion of said member and engaging the pivot pin.

6. In a device of the character described, an arm, a pivot pin disposed adjacent one end of the arm and extending laterally thereto, a slotted spacer member interposed between the pin and the arms, another slotted member secured to the arm and serving to clamp the pin and spacer member against the arm with the pin between the first and second members, and a relatively stationary journal bracket extending into said slots and engaging an intermediate portion of said pin.

In testimony whereof, I have hereunto set my hand.

JAMES C. REA.
